UNITED STATES PATENT OFFICE.

GUSTAVE LUNDBERG, OF LOGAN, UTAH TERRITORY.

WEIGHING-SCALE.

SPECIFICATION forming part of Letters Patent No. 447,691, dated March 3, 1891.

Application filed October 30, 1890. Serial No. 369,843. (No model.)

To all whom it may concern:

Be it known that I, GUSTAVE LUNDBERG, a citizen of the United States of America, residing at Logan, in the county of Cache and 5 Territory of Utah, have invented certain new and useful Improvements in Weighing-Scales; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 This invention relates to improvements in weighing-scales.

The object of the invention is to provide a weighing-scale having an oscillating indicator for ounces and fractions thereof operated by 20 the main scale-beam, which carries an adjustable weight and acts upon a series of supplemental weights, whereby the overweight will be indicated when the beam is overbalanced, as well as the weight of vessels placed in the 25 scale-pan ascertained before setting the sliding weight carried by the main scale-beam; and the invention consists in the construction and combination of the parts, as will be hereinafter fully set forth, and particularly pointed 30 out in the claims.

In the accompanying drawings, forming part of this specification, Figure 1 is a perspective view of a weighing-scale constructed in accordance with my invention. Fig. 2 is a 35 longitudinal sectional view. Fig. 3 is a sectional view taken on the line $x-x$ of Fig. 2, and Fig. 4 is a sectional view on the line $y-y$ of Fig. 2.

A refers to the base to which the supporting-frames are attached, said supporting-frames consisting of uprights B B, upon which the main beam C is fulcrumed by the employment of the usual knife-edge bearings. Upon the supporting-frame between the uprights B 40 B is located a bifurcated bearing b, through which passes a pin for pivotally connecting thereto bars d and d'. At the opposite end of the base A are secured standards E E, which carry at their upper ends a plate F, 45 having suitable gage-marks thereon, said gage-marks commencing at zero and being spaced

to represent fractions of ounces. Over each face of the plate F passes the end of a bifurcated pointer G, which is carried by a weighted crank-arm H, journaled between suitable supports I and I', the end of said crank-arm having a projecting pin h, which enters a slot in a vertically-moving basket J, hung upon the end of the scale-beam C, to move between the side pieces I' and I² of the frame which contains 55 the series of weights. This basket J is connected at its central lower portion by a pivot-pin to the bar d', hereinbefore referred to, and at one side extends the projection having a horizontal slot into which passes the 60 pin h, carried by the arm H, so that as this basket moves up and down the pointer G will move over the scale-plate F. When the pointer G is to one side of the zero-mark, it will indicate that the scales are not properly balanced, 65 and as it moves toward the opposite end it will indicate the fractions of ounces as positioned. The arm H is weighted on the side opposite the extended portion to properly balance.

75 Between the vertical frames I' and I² are hung a series of weights K, which are of less width than the distance between the side pieces of the basket J, and each of these weights is provided with pins k k, which enter recesses i i in the side pieces I' and I², these recesses being of diminishing depth, as shown in Fig. 3. The weight K, which is supported in the long slot, is positioned immediately above the side frame of the basket, 80 but not in contact therewith when the scales are properly balanced. To prevent longitudinal movement of the weights K, I attach to the side pieces I' and I² plates l², against which the ends of the pins k will contact and prevent such movement. By providing V-shaped slots i friction contact with the edges of said slots is avoided when the pins rest upon the basket J.

90 The portion of the weighing-scales thus far described may be used for postal or other scales without the other parts of my invention, as when a light weight is placed in the scale-pan to overbalance the beam the ounces and fractions thereof will be properly indicated by the pointer upon the graduated plate F.

The beam C is fulcrumed upon the supports B B, and upon the short end is hung a frame L, having a hollowed-out central portion and vertical open-ended slots, through which the 5 pivot-pins attached to the side pieces pass. The upper portion of this frame L carries the usual pan M, and to the lower end is secured a depending bifurcated pin, to which the bar d is pivotally secured. To the upper edges 10 of the side pieces of the beam C is secured a plate N, provided with a longitudinal slot n, adjacent to which is a scale, and through this slot passes a screw m, which engages with a bar C' at its lower end and carries an indicator m' at its upper end. The bar C' is secured at one end to a sliding weight W, secured to a top plate c, which extends over the 15 edges of the beams C to hold the weight movable thereon, and said weight W is of a sufficient size to counterbalance the frame L and parts attached thereto, which are located beyond the fulcrum of the bars C C when the weight W and plate c, attached to said weight, abut against the plate N. The bar C' passes 20 through an opening in the depending wall or transverse guide c', located at one end of the plate N, and this bar C' is preferably made up of a slotted tube, within which lies a bar O, having notches o for engagement with the 25 lower portion of the wall or guide c', and beyond this plate the flat bar O is given a half-turn to provide a flat spring portion, the tendency of which is to throw the outer end of the bar downward to hold the notches therein in 30 contact with the opening in the wall or transverse guide c'. The inner end of the spring-bar O is screwed into or otherwise secured to the weight, and said weight is adjusted by said bar, which can be moved so that the 35 notches therein will engage with the lower portion of the opening in the wall or transverse guide c'.

By the use of the improved scale hereinbefore described it will be readily seen that by 40 properly moving the weight W, which is attached to the plate c, the edges of which overlap or lie over the upper edges of the bars C C and slide thereon, which is done by raising the spring-bar and drawing or pushing the 45 same until the indicator m' is at the proper point, the weight will be held by the spring-bar in the position in which it is placed, and the indicator m' will indicate the number of pounds or fractions thereof which the pan will 50 receive before depressing the main beam. In weighing goods after the weight and indicator are set, as described, when the scale-beam is depressed slightly, the pan will contain the exact weight of material indicated by the 55 pointer m', and if overweight is placed in the pan the beam will be further depressed and the vertically-movable weights K will coact with the beam and indicate the excess or overweight. In handling ordinary groceries the 60 dealer by the use of my improved scale can ascertain exactly the amount of overweight which they give the purchaser. These scales 65

may also be used in weighing goods which have to be placed in dishes, cans, or other suitable receptacles, as the weight of the receptacle can be ascertained by movement of the pointer G, so that in order to give proper weight it will be necessary to place sufficient material in the scale-pan to depress the beam and move the pointer G to the point representing the weight of the receptacle. 75

This device is convenient and saves time and indicates to the dealer the exact amount of overweight.

It is obvious that minor changes may be 80 made in the construction and arrangement of the parts without departing from the spirit of my invention as indicated in the claims.

Having thus described my invention, what I claim as new, and desire to secure by Letters 85 Patent, is—

1. The combination, in a weighing-scale, of a main beam, a support pivoted to one end thereof, a sliding weight W, and a bar O for adjusting the sliding weight, said weight having attached thereto a slotted tube carrying 90 an indicator which moves over a scale-plate attached to the beam, substantially as set forth.

2. The combination, in a weighing-scale, of the pivoted beam C, having a slotted scale-plate, a movable weight carrying a slotted tube and a locking-bar O, and a transverse guide or wall having an opening through which the slotted tube and locking-bar pass, said locking-bar having notches, substantially as 100 set forth. 95

3. In a weighing-scale, the combination of a main beam consisting of parallel side pieces suitably fulcrumed, and a pan-carrying frame through which the tube C' and locking-bar 105 pass, said pan-carrying frame being pivotally attached to the side pieces of the beam and provided with a link or bar d, connecting the same with the base-frame, substantially as set forth. 110

4. The combination, in a weighing-scale, of the pivoted beam C, having a movable sliding weight and means for adjusting and holding the same, a slotted scale-plate over which the indicator passes, a pan-supporting frame hung upon the side pieces of the beam and connected to the base by a bar d, and a basket hung upon the opposite end of the beam, said basket being located beneath a series of vertically-movable weights and provided with a slotted 120 bar with which the arm of an oscillating pointer engages, substantially as set forth. 115

5. In combination with a main beam C and attachments therefor, the vertical supports I' and I², having slots for supporting a series of vertically-moving weights, and a basket or frame located beneath said weights and pivotally attached to the end of the main beam, said basket being adapted to operate an indicator, substantially as set forth. 125 130

6. In combination with the main beam C of a weighing-scale, a vertically-moving basket or frame J, a bar d' for connecting the same to the base, a frame L, attached to

the beam C C at the opposite end to which the frame J is secured, and bar d, connecting the lower end of the frame L to the base, substantially as set forth.

5 7. In combination with a weighing-scale constructed substantially as shown, standards attached to the same base and carrying a graduated plate, a pivoted pointer adapted to move in proximity thereto, and means for connecting the same to a movable basket suspended from the scale-beam, substantially as set forth.

8. In a weighing-scale, the combination, with 15 the scale-beams C, carrying at one end a basket, said basket having a horizontal slot, of an indicator or pointer G, carried by a weighted arm H, said arm being pivotally secured to a support and provided with a projecting pin which engages with the slot in the basket, together with a scale-plate F, over 20 which the indicator travels, substantially as set forth.

9. In combination with a series of weights K, supports therefor having V-shaped slots, within which the pins carrying the weights lie, 25 and a vertically-movable basket or frame at-

tached to the scale-beam, substantially as set forth.

10. The combination, with a scale-beam constructed substantially as set forth and provided with an adjustable weight, of a slotted 30 tube C' and spring locking-bar O, having notches o, said bar being twisted so that the portion in which the notches are located is vertical and its spring tendency downward, as set forth.

11. In combination with a weighing-scale, a beam C, pan-supporting frame L, bars d and d', pivoted as shown, and a basket or frame J, attached to the main beam and bar d', said basket being adapted to engage with a series 40 of vertically-moving weights and operating an oscillating pointer which moves over the faces of the scale-plate F, substantially as set forth.

In testimony whereof I affix my signature in 45 presence of two witnesses.

GUSTAVE LUNDBERG.
